NEEDLE PAD

Genevieve Mock, Richmond Hill, N. Y.

Application August 1, 1942, Serial No. 453,154

4 Claims. (Cl. 51—182)

This invention relates to new and useful improvements in a needle pad.

More specifically, the invention proposes the construction of a needle pad characterized by a tubular casing of a size to fit frictionally into the hole formed in a spool of thread and formed with a partition extended completely therethrough in a manner to divide the interior of the casing into separate compartments.

A further object of the invention proposes mounting a needle pad in one of the compartments to receive a sewing needle and to provide the sides of the tubular casing with grooves permitting a length of thread engaged with the needle to be wound about the casing before the casing is inserted into the opening in the spool.

It is another object of this invention to mount another needle pad containing a powdered abrasive material within the other compartment of the casing so that when a needle is engaged into this latter pad its point will be renewed and sharpened.

Still further the invention proposes pivotally mounting the partition so that it may be swung towards the pad containing the abrasive material in a manner to compress this pad to more effectively renew and sharpen the point of the needle.

Another object of the invention proposes mounting a plurality of needle pads in accordance with this invention upon a ring in a manner to form a unit of these pads to receive a greater number of needles.

Still another object of this invention proposes the construction of a needle pad which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a needle pad constructed in accordance with this invention.

Fig. 2 is a vertical sectional view taken on the line 2—2 of Fig. 1.

Fig. 3 is a partial vertical sectional view taken on the line 3—3 of Fig. 1.

Fig. 4 is a perspective schematic illustration of the needle pad mounted within the opening of a spool.

Fig. 5 is a perspective view of a plurality of

needle pads constructed in accordance with this invention and connected together as a unit.

The needle pad in accordance with this invention, includes a tubular casing 10 formed with longitudinal grooves 11 on diametrically opposite sides thereof. The tubular casing 10 is formed of metal and is of a diameter to be frictionally forced into an opening extended through a conventional spool 12 for sewing thread.

10 The interior of the casing 10 is divided into adjacent compartments by means of a partition 13. The partition 13 is extended laterally of the casing 10 between the grooves 11 and has its top end pivotally attached upon a pin 14 extended between the top ends of the grooves 11. The bottom end of the partition 13 is projected slightly beyond the bottom end of the casing 10 to be pivoted relative to the casing 10 for a reason that will be hereinafter set forth.

15 A needle pad 15 is mounted in one of the compartments of the casing 10 to one side of the partition 13. This pad is characterized by a cloth cover 16 enclosing felt or other soft material 17. A needle 18 is adapted to be stuck into the pad 15 and if the string 19 is long enough it may be wound about the casing 10 in alignment with the grooves 11 before the casing 10 is inserted into the opening in the spool 12.

20 A second needle pad 20 is mounted in the other compartment of the casing 10 on the other side of the partition 13. This pad 20 also has a cloth cover 21 enclosing felt or other soft material 22 which is impregnated with an abrasive material. The abrasive material is in the form of a carborundum dust so as to sharpen and renew a needle when its point is pushed into the pad 20. It is possible to compress the pad 20 by pivoting the partition 13 towards the pad. This is done by gripping the free projected end of the partition 13 and manually forcing it towards the pad 20 to compress the pad 21 to increase the efficiency of operation of the carborundum dust when the point of the needle is pushed into the pad.

25 The top of the pad 20 is marked with a large capital C to enable users of the article to distinguish between the pad 20 having the abrasive material and the pad 15 which does not have the abrasive material.

30 The manner of using the needle pad is as follows:

35 The needle pad is inserted into the opening in the spool 12 and its casing 10 is of a length so that its ends will be substantially flush with the ends of the spool with the free end of the partition 13 extending from the adjacent end of the spool 12.

Needles 18 may be inserted into the pad 15 and if they have an extremely long piece of thread, the thread may be wound about the casing 10 by first removing the casing and winding the thread about the grooved portion 11 of the casing 10. The casing is then restored within the opening in the spool 12.

If the needle becomes dull or rusty and needs renewing, the pointed end of the needle is inserted into the pad 20 marked with the large C. This is the pad which contains the abrasive material and if the needle is moved about within this pad the abrasive material will act to restore the needle to usefulness. The efficiency of this pad 20 may be increased by pivoting the partition 13 to compress the pad 20 and cause the abrasive material within this pad to act upon the surfaces of the needle more forcefully.

In Fig. 5 a plurality of needle pads constructed in accordance with this invention are illustrated. The top of each of these pads and more particularly the top end of the casing 10 of each of these pads is formed with a lug 25. These lugs 25 are adapted to be clamped in position upon a ring 26 at points equally spaced from each other to connect the needle pads together as a unit.

While the drawing illustrated a unit of four needle pads, it is pointed out that this is merely by way of illustration and that a greater or less number of needle pads may be engaged in position on one ring.

In other respects this form of the invention is similar to that previously described; and like reference numerals identify like parts in each of the several views.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new and desire to secure by United States Letters Patent is:

1. A needle pad, comprising a tubular casing, a partition mounted within said casing dividing it into compartments, a needle pad mounted in one of said compartments, and a needle pad containing an abrasive material mounted within the other compartment for sharpening a needle as it is stuck into said pad, said pad containing said abrasive material being marked with a large identifying C.

2. A needle pad, comprising a tubular casing, a partition mounted within said casing dividing it into compartments, a needle pad mounted in one of said compartments, and a needle pad containing an abrasive material mounted within the other compartment for sharpening a needle as it is stuck into said pad, said partition being pivotally supported to be manually pivoted for compressing said latter-named pad to more effectively sharpen a needle stuck into said pad.

3. A needle pad, comprising a tubular casing, a partition mounted within said casing dividing it into compartments, a needle pad mounted in one of said compartments, and a needle pad containing an abrasive material mounted within the other compartment for sharpening a needle as it is stuck into said pad, said partition being pivotally supported to be manually pivoted for compressing said latter-named pad to more effectively sharpen a needle stuck into said pad, said partition having one of its ends freely mounted on a pin extended across one end of said casing and comprising said pivotal mounting and the other of its ends projected beyond the other end of said casing to be gripped to facilitate pivoting of said partition.

4. A needle pad, comprising a plurality of tubular casings, each of said casings, comprising a partition mounted within said casing dividing it into compartments, a needle pad mounted in one of said compartments, a needle pad containing an abrasive material mounted in the other of said compartments, and means for connecting said tubular casing together as a unit.

5. GENEVIEVE MOCK.
